Primary Examiner — Shawn T Gingrich*Assistant Examiner* — Bryan N. Melvin(74) *Attorney, Agent, or Firm* — Ruggiero McAllister & McMahon LLC(57) **CLAIM**

The ornamental design for a triangular electrical connector with flange, as shown and described.

DESCRIPTION

FIG. 1 is a top, front, right side perspective view of my new design of a triangular electrical connector with flange.

FIG. 2 is a front side elevational view thereof.

FIG. 3 is a left side elevational view thereof.

FIG. 4 is a rear side elevational view thereof.

FIG. 5 is a right side elevational view thereof.

FIG. 6 is a top plan view thereof; and,

FIG. 7 is a bottom plan view thereof.

The broken lines in FIGS. 1, 2 and 4 represent environment only, and form no part of the claimed design.
